UNITED STATES PATENT OFFICE.

SAMUEL WILLIAM TURNER, OF CANONBURY, LONDON, ENGLAND, ASSIGNOR TO YOST WRITING MACHINE COMPANY, OF ILION, NEW YORK, A CORPORATION OF NEW YORK.

TYPE-WRITING MACHINE.

1,050,815.

Specification of Letters Patent. Patented Jan. 14, 1913.

Original application filed January 31, 1911, Serial No. 605,732. Divided and this application filed September 7, 1912. Serial No. 719,066.

To all whom it may concern:

Be it known that I, SAMUEL WILLIAM TURNER, a subject of the King of Great Britain and Ireland, residing at 11 Douglas Road, Canonbury, in the county of London, England, have invented new and useful Improvements in Type-Writing Machines, of which the following is a specification.

This invention relates to typewriting machines, and has for its object improvements in the arrangement and construction of driving and escapement mechanism for the platen carriage, whereby the carriage can be made to travel in either direction. These features in a typewriting machine are especially useful in the case of writing Turkish and Arabic.

The invention consists in certain features of construction and combinations and arrangements of parts, all of which will be fully set forth herein and particularly pointed out in the claims.

The present application is a division of my prior application filed January 31, 1911, Serial No. 605,732, and the present application is directed more especially to the means whereby the carriage can be driven in either direction at will under the control of the escapement.

In order that the invention may be the better understood, I will now proceed to describe the same in relation to the accompanying drawings, reference being had to the letters and figures marked thereon.

Like letters refer to like parts in the various figures.

Figure 1 is a right-hand end view of the carriage showing the means for drawing the forward rack out of engagement with the pinion. Fig. 2 is a rear sectional elevation on a reduced scale and showing the carriage driving mechanism. Fig. 3 is a left-hand end view of the carriage showing means for withdrawing the rear rack out of engagement with the pinion. Fig. 4 is a fragmentary plan view of the two racks and the feed pinion.

The escapement is of the rotary type and connects with the carriage by means of a pinion co-acting with racks carried by the carriage. According to this invention I provide two racks *a* and *b*, one on each side of the pinion *c*, the said racks being alternately

rocked into engagement with the escapement pinion at the will of the operator. 55 The forward rack *a* is pivoted on the carriage on screws *a*¹ and is provided with a bent arm *a*², Fig. 1. The disengaging movement of the rack about the axis of the screws *a*¹ is effected by means of a thumb 60 lever *a*³ pivoted at *a*⁴ and having a projecting pin *a*⁵ which engages with the bent arm *a*². Springs *a*⁶ are provided to return the rack *a* into operative position. The thumb lever *a*³ can be maintained in the position 65 shown in Fig. 1 by means of a pivoted detent *a*⁷ so as to maintain the rack *a* out of engagement with the pinion *c*. The rack *b* is pivoted to the carriage frame by means of screws *b*¹ and is operated by means of a 70 thumb lever *b*², Fig. 3, pivoted to the frame by a screw *b*³, the lower end of the lever *b*² engaging with an upwardly projecting rib *b*⁴. The thumb lever *b*² can be maintained in its actuated position by means of a pivoted 75 detent *b*⁵ which engages with the upper end of the lever *b*². Springs *b*⁶ are provided to return the rack *b* into its operative position.

When a particular direction of travel of 80 the carriage is desired, the operator by regulating the position of the thumb levers *a*³ and *b*² allows either one or other rack *a* or *b* to come into operative connection with the escapement pinion *c* according to the direction of travel of the carriage desired; the 85 racks being on the opposite sides of the pinion *c*, permits motion of the carriage *d* in either direction although the pinion *c* and the escapement wheel have a uni-directional 90 motion. From the above description it will be obvious that when one of the keys *a*³ and *b*² is locked by its latch *a*⁷ or *b*⁵, the other of said keys becomes a release key for the carriage. 95

In operating the carriage *d* I use a single spring drum *d*¹, the cord *d*² of which passes around a pulley or snatch block *d*³, Fig. 2, and is attached to the carriage at *d*⁴ in the usual way but at the left-hand end of said carriage. The pulley or snatch block *d*³ is adapted to be readily attached either to the carriage at *d*⁵ or to the main frame of the machine at *d*⁶ and in this way the spring exerts a pull on the carriage either in 100 one or the other direction according to

whether the pulley or snatch block is carried by the carriage d , or is attached to the frame. If the pulley or snatch block d^3 is attached to the frame as shown in Fig. 2, the carriage will have a motion under the action of the spring drum from right to left as viewed in said figure; whereas if the pulley or snatch block d^3 is attached to the carriage at d^5 , the carriage will then have a motion from left to right as viewed in Fig. 2, which is a rear view.

The spacing is obtained by means of two escapement wheels e and f , co-axially arranged on the shaft g which is driven by the pinion c through the intermediation of a clutch c^1 ; in combination with certain dogs which are not shown herein, but are shown and described in the parent application Sr. No. 605,732, above referred to. The escapement wheel e is rigidly fixed to the shaft g while the escapement wheel f is loosely mounted upon the same and is permitted to revolve freely through a fixed arc controlled by stops carried by the shaft g or by the fixed escapement wheel e . In the form illustrated in the drawings, said stops comprise a circumferential slot f^2 arranged in the boss of the wheel f , and a screw g^1 rigidly fixed in the shaft g . The escapement wheel f is spring pressed in relation to the fixed escapement wheel e in one direction by means of the spiral spring e^4 ; the amount of movement being limited by the stops hereinbefore described. A feed dog is adapted to engage first one wheel and then the other, as will be understood. As far as the present invention is concerned, the shaft g can be controlled by any suitable typewriter escapement.

The operation of my machine is as follows:—For writing ordinary Arabic or Turkish, the pulley d^3 is attached to the frame of the machine at d^4 , the thumb lever b^2 is actuated and maintained in position by a detent b^6 , the thumb lever a^3 being used as a release key in the usual way. The carriage now moves from the operator's left to his right under control of the escapement mechanism, the line of writing reading from right to left. In order that figures may be written it is necessary to reverse the direction of the line of writing, the pulley d^3 is therefore attached to the carriage at d^5 , the thumb lever b^2 is permitted to resume its normal condition and the thumb lever a^3 is drawn toward the operator and maintained in position by the detent a^6 , the lever b^2 being used as the ordinary release lever.

It will be seen that by the use of a uni-directional escapement and escapement pinion, it is possible by my invention to retain all the usual devices common to typewriting machine escapements, such as back spacing devices and the like.

What I claim as new and desire to secure by Letters Patent, is:—

1. In a typewriting machine in combination, a platen carriage, a rotary uni-directional escapement, two adjustable racks engaging on opposite sides of a pinion controlled by the escapement, arms pivoted to the platen carriage and supporting each rack independently of the other and adapted to swing each said rack independently into and out of engagement with the pinion, hand operated means carried by the carriage for controlling the position of the racks, and means for continuously spring pressing the platen carriage in either one direction or the other; the movement of the said platen carriage being controlled by the step-by-step movement of the said escapement pinion, substantially as described. 70

2. In a typewriting machine in combination, a platen carriage, a rotary uni-directional escapement, two adjustable racks engaging on opposite sides of a pinion controlled by the escapement, means for operatively engaging either one or other rack 80 with said pinion at will, a single spring barrel, a cord or chain wound around same and having its end fastened to the carriage, a pulley or snatch block threaded on said cord or chain and attaching means both upon the frame and upon the carriage for engaging the pulley or snatch block at will to cause the carriage to be spring pressed in either one direction or the other, according to the direction of feed required, the movement of 90 the said platen carriage being controlled by the step by step movement of the said escapement pinion, substantially as described. 95

3. In a typewriting machine, the combination of a carriage, a rotary uni-directional escapement, a pinion controlled by said escapement, two racks independently engageable with said pinion on opposite sides thereof, one of said racks adapted to control said carriage for feed in one direction and the other of said racks being adapted to control said carriage for feed in the other direction, means for propelling said carriage in either direction at will, and carriage release devices for temporarily moving out of engagement the rack that is in use. 105

4. In a typewriting machine, the combination of a carriage, a rotary uni-directional escapement wheel, two racks, means for gearing said racks independently with said escapement wheel, one of said racks being used to control the carriage for feed in one direction and the other of said racks for feed in the other direction, means for propelling said carriage in either direction at will, and carriage release devices for moving out of engagement the rack that is in use. 120

5. In a typewriting machine, the combi- 125

- nation of a carriage a rotary uni-directional escapement, two racks, gearing for connecting said racks alternatively with said escapement, spring means for pressing said two racks into engagement with said gearing, means for holding one of said racks out of engagement, and means for moving out of engagement the rack that is in use in order to release the carriage from its escapement.
- 5 6. In a typewriting machine, the combination of a carriage, means for propelling said carriage in either direction at will, a rotary uni-directional escapement, a pinion controlled by said escapement, two racks for 10 engagement with said pinion on opposite sides thereof, springs for pressing said racks toward said pinion, means for holding one of said racks out of engagement, and means for moving the other of said racks temporarily out of engagement to release the carriage.
- 15 7. In a typewriting machine, the combination of a carriage, a spring for driving said carriage, a band for connecting said 20 spring with said carriage, said band being connected to said carriage near one end thereof, a pulley over which said band runs, and means for attaching said pulley to the stationary framework or to the other end of said carriage in order to feed said carriage one way or the other.
- 25 8. In a typewriting machine, the combination of a carriage, escapement mechanism, two feed racks movable independently into and out of operative position, one of said racks being used to control the carriage for feed in one direction and the other of said racks for feed in the other direction, means for propelling the carriage in either direction at will, and carriage release devices for moving out of engagement the rack that is in use.
- 30 9. In testimony whereof I have signed my name to this specification in the presence of two subscribing witnesses.
